United States Patent Office

Des. 220,685
Patented May 11, 1971

220,685

AIR-SUPPORTED STRUCTURE

James Scott Stineman, 615 W. Civic Center Drive,
Suite 215, Santa Ana, Calif. 92701

Filed Feb. 17, 1970, Ser. No. 21,474

Term of patent 14 years

Int. Cl. D25—04

U.S. Cl. D13—1

FIG. 1.

FIG. 2.

FIG. 3.

FIG. 4.

FIG. 1 is a front and right side perspective view of an air-supported structure;

FIG. 2 is a plan view of my air-supported structure;

FIG. 3 is a rear elevational view of my air-supported structure; and

FIG. 4 is a left side elevational view of my air-supported structure.

I claim:

The ornamental design for an air-supported structure, substantially as shown and described.
